ADJUSTABLE AND DETACHABLE HANDLE CONNECTION

Charles S. Trippeda, New York, N. Y.

Application September 25, 1933, Serial No. 690,922

9 Claims. (CL. 306—2)

This invention relates to a device or means for adjustably and detachably connecting a staff or rod handle with an implement such as a floor brush or broom, window cleaning implement and other analogous implements.

The invention contemplates a handle connection of the indicated character which makes it possible to more conveniently manipulate the implement in corners and places which would be difficult to get at with implements having the usual fixed handle; and to make it possible to conveniently carry the implement about from place to place when not in use, and for the convenient packing and shipping of a single implement or numerous implements.

The invention consists in the simple, inexpensive, practical, and neat connecting device as hereinafter fully described and illustrated in the accompanying drawing and as set forth in the appended claims.

In the drawing—

Figure 1 is a transverse section of a cleaning element selected to illustrate the handle connection shown applied thereto, the same being shown in section;

Fig. 2 is a perspective view of the cap used in connection with the device;

Fig. 3 is a perspective view of the rotatable part of the device with which the handle may be connected;

Fig. 4 is a plan of the implement and showing the connection of the handle, a portion of the latter being shown in one position in full lines and in other adjusted positions in dotted lines;

Fig. 5 is a front side view of the implement and handle connection, a portion of the handle being shown.

In the drawing a floor brush has been selected to illustrate the handle connecting device of the invention. This floor brush consists of a wooden head or block 10 to which the usual bristles 11 are secured. The connecting device includes a part 12 in the form of a block of metal having a round bore 13 which accommodates an element 14 in the form of an arbor on which the part 12 may rotate. The element 14 has a reduced portion 15 which provides a shoulder 16. The portion 15 has threads 17. The upper end of the element has a head 18, the upper surface of which is convex. The block 10 of the brush has a hole bored therein centrally thereof to receive the threaded portion 15 of the element 14, after the part 12 has been slipped on the element 14 and a washer 19 has been slipped on the portion 15 against the shoulder 16. A nut

20 is then screwed on the threaded end of the portion 15 to secure the element 14 in fixed position on the block 10. The element 14 thus secured will provide an axis disposed perpendicular to the longitudinal and transverse axes 60 of the block 10. In this manner the part 12 will be mounted for rotation on the element 14, it being apparent that the part 12 is disposed between the head 18 and the washer 19 to thus be held against displacement. The part 12 embodies a nut since the same has a threaded bore 21 therein which is disposed upwardly at an angle with respect to the axis of the element 14. A part 22 made of metal is secured by screws 23 to the block 10 to provide a cover therefor. This 70 part 22 is made of metal which may be chromium or nickel plated to add to the finish and give a neat appearance to the brush. The part 22 has a central opening providing an edge portion 24 concentric to the element 14 and surrounding the 75 same below the head 18 in spaced relation to the latter. Since the part 22 is made of metal, the edge portion 24 will be flexible so as to be pressed into engagement with an edge portion 25 of the part 12. A staff or rod handle 26 is provided, and 80 its lower end has a metal ferrule 27 which carries a screw stud 28. The threads of the stud 28 are complementary to the threads of the bore 21 so that the stud 28 may be screwed into the bore. The handle 26 may thus be connected 85 with the brush and may be swung to various radial positions of adjustment with respect to the element 14 and, therefore, may be adjusted to various positions with respect to the brush as indicated in Fig. 4. By turning the handle 26 90 the stud 28 may be screwed into the bore 21 until the ferrule bears against the edge portion 24, pressing the same in contact with the edge portion 25 of the part 12, to secure the handle 26 in the desired adjusted position. It is to be understood that the handle 26 will be secured in the desired adjusted position by the engagement of the ferrule 27 with the edge portion 24 without necessarily pressing said portion 24 in contact with the edge portion 25 of the part 12. 100

In accordance with another feature of the invention, use is made of a concavo-convex cap 29 having a central hole 30 therein and a radial notch 31 opening through the outer peripheral edge thereof, and depending portions 32 at the 105 opposite sides of the notch, respectively. The portions 32 are integral portions of the cap and are provided in making the notch 31. The cap 29 is held in place for rotation on the head 18 of the element 14 by a cap screw 33 screwed into 110

the element 14. The spaced portions 32 embrace the opposite sides of the part 12 so as to rotate with the latter. The cap 29 in conjunction with the part 12, serves to close the space 5 between the head 18 and the edge portion 24 of the part 22, and also gives a completed finish to the connection. The cap 29 may be chromium or nickel plated similar to the cover part 22.

Attention is called to the fact that in securing 10 the handle 26 in the desired position of adjustment, the ferrule 27 will engage the cap 29 as well as the edge portion 24 of the part 22, although it is not necessary that the ferrule 27 should so engage the cap 29.

15 The handle 26 may be detached for the purposes mentioned hereinbefore. The handle 26 easily may be detached by turning the same to unscrew the stud 28 from the bore 21 in the part 12.

20 What I claim is:

1. A handle connecting device comprising a block, a handle, a fixed member on the block to provide an axis perpendicular to the longitudinal and transverse axes of the block, a part 25 rotatable on said member, a second fixed member on said block surrounding said rotatable part, and said rotatable part having means for engaging the lower end of the handle so that said end may engage said second fixed member, to thus secure the handle in various positions of adjustment with respect to said fixed members.

2. A handle connecting device comprising a block, a handle, a fixed member on the block to provide an axis perpendicular to the longitudinal and transverse axes of the block, a part 30 rotatable on said member, a second fixed member on said block providing an edge concentric to said rotatable part, and said rotatable part having means for engaging the lower end of the handle so that said end may engage said second fixed member, to thus secure the handle in various 35 positions of adjustment with respect to said fixed members.

3. A handle connecting device comprising a block, a handle, a fixed member on the block to provide an axis perpendicular to the longitudinal and transverse axes of the block, a part 40 rotatable on said member, a second fixed member on said block surrounding said rotatable part, and said rotatable part having means for threadingly engaging the lower threaded end of the handle so that said end may engage said second fixed member, to thus secure the handle in various 45 positions of adjustment with respect to said fixed members.

4. A handle connecting device comprising a block, a handle, a fixed member on said block, a part 50 rotatable on said member, a second fixed member on said block surrounding said rotatable part in spaced relation thereto, and said rotatable part having means for engaging the lower end of the handle so that said end may engage said second fixed member, to thus secure the handle in various 55 positions of adjustment with respect to said fixed members, and in combination, a cover member which is rotatably mounted on said first

fixed member and engaged with said rotatable part, for the purpose of closing the space between said fixed members.

5. A device for adjustably connecting a handle with an implement which comprises a handle, a fixed arbor carried by said implement, a part 80 rotatable on said arbor, and a metal cover fixed on the top of said implement, said cover having an opening therein, through which said arbor projects and providing an edge portion concentric to said arbor, and said rotatable part having means for engaging the lower end of the handle so that said end may engage said edge portion, to thus secure the handle in various positions of adjustment with respect to said implement.

6. A handle connecting device comprising a block, a handle, an arbor having a head on one end and the other end being threaded and also having a shoulder between the ends thereof, a nut 85 for threading engagement with the threaded end to secure the arbor in fixed position on said block, a washer surrounding the arbor and disposed against said shoulder and block, a part rotatable on said arbor and held against axial movement by said head and washer, a fixed continuous portion on said block surrounding said arbor concentric with respect thereto, and said rotatable part having means for engaging the lower end of the handle so that said end may engage said continuous portion, to secure the handle in various radial 90 positions with respect to said arbor.

7. A handle connecting device comprising a block, a handle, an arbor fixed to said block, a part 95 rotatable on said arbor, a cover member which is rotatably mounted on said arbor, said rotatable part having means for engaging the handle to secure the handle in various positions of adjustment with respect to said block, and means on said cover member engaging said rotatable part 100 to cause the former to rotate with the latter.

8. A handle connecting device comprising a block, a handle, an arbor fixed to said block, a part 105 rotatable on said arbor, a cover member which is rotatably mounted on said arbor, said rotatable part having means for engaging the handle to secure the handle in various positions of adjustment with respect to said block, and means on said cover member engaging said rotatable part 110 to cause the former to rotate with the latter, said cover member having a notch therein through which the handle extends.

9. A handle connecting device comprising a block, a handle, an arbor fixed to said block, a part 115 rotatable on said arbor, a cover member which is rotatably mounted on said arbor, said rotatable part having means for engaging the handle to secure the handle in various positions of adjustment with respect to said block, said cover member engaging said rotatable part to cause the 120 former to rotate with the latter, said cover member having a notch therein through which the handle extends, and depending portions on the cover member engaging said rotatable part to cause the former to rotate with the latter.
